(57) **CLAIM**

The ornamental design for a wireless hearing device receiver, as substantially shown and described.

DESCRIPTION

FIG. 1 is a front perspective view of the wireless hearing device receiver;

FIG. 2 is a front view of the wireless hearing device receiver; FIG. 3 is a right side view of the wireless hearing device receiver;

FIG. 4 is a left side view of the wireless hearing device receiver;

FIG. 5 is rear view of the wireless hearing device receiver;

FIG. 6 is a top view of the wireless hearing device receiver; and,

FIG. 7 is a bottom view of the wireless hearing device receiver.

The portions of the wireless hearing device receiver shown in broken lines do not form part of the claimed design.
